DISPLAY DEVICE

Conrad Vásquez, New York, N. Y.

Application February 3, 1951, Serial No. 209,245

2 Claims. (Cl. 35—49)

1

This invention relates to a new and improved turnable figure or object display device, and more particularly to a device for manipulating a three dimensional figure or object into any desired position for art or anatomical study and observation, or display.

Its principal object is to provide a device for manipulating a three dimensional figure or object into any desired position, the device having means for rotating or turning the figure or object both around its transverse axis and longitudinal axis for study, display and observation thereof from every conceivable angle and position.

Another object of the invention is to provide a turnable figure or object display device in which the means for rotating or turning the object or figure is a simple and compact unit, the means for rotating the figure or object around its transverse axis being carried by the means for rotating the figure or object around its longitudinal axis.

Another object of the invention is to provide a novel turnable figure or object display device, the device having indicia and pointer means to indicate any disposed angularity desired.

Another object of the invention is to provide a turnable figure or object display device which is economical to manufacture and assemble, and which may be readily used and operated by anyone.

Other objects of the invention will be set forth in the following description and drawings to which—

Fig. 1 is a front elevational view of the device;

Fig. 2 is a side elevational view thereof;

Fig. 3 is a vertical section through the essential operative parts of the device; and

Fig. 4 is a sectional view on the line 4—4 of Fig. 3.

Referring to the drawing, the device is mounted on the vertical support 10, which in turn is supported by the base 11. Upright 10 and base 11 may be integral or may constitute separate members which can be secured to each other in any suitable manner to form the bracket support B. The configuration and construction of said bracket support B are of no consequence as far as the invention herein is concerned, and any desired support may be employed as the mounting medium. Likewise, said bracket support B may be made of wood, metal, plastic, or any other desired material.

As shown in Fig. 3, the upright 10 is provided with a centrally located opening 12, in which is

5 frictionally fitted the bushing 13, the said bushing being provided with the peripheral annular outwardly extending flange 14, the inner face of said flange abutting the rear face of upright 10 adjacent opening 12, thereof.

10 Turnably located in bushing 13 is the longitudinal tubular housing or hollow cylindrical member 15, each end of said housing extending beyond the respective ends of said bushing. It will be noted that the portion of the external circumferential wall of said housing which is located within bushing 13 abuts the inner circumferential wall of said bushing.

15 The end of tubular casing 15 adjacent annular flange 14 of bushing 13 is designated as the rear end thereof, and the opposite end as the forward end thereof. The rear end of said tubular housing is closed by the knurled knob or hand-piece 16, and the forward end by the plug 16a. The said knob 16 is provided with an integral reduced 20 mounting flange 17, which frictionally engages the outer circumferential peripheral edge of tubular housing 15 adjacent its rear end. The further connection of said knob 16 with said tubular housing 15 is effectuated by the set-screw 18, which extends through a small transverse bore in flange 17. It will be noted from Fig. 3 that the facing edge surfaces of flanges 17 and 14 abut each other.

25 A circular dial plate 19, having azimuth calibrations thereon, is mounted on the front face of upright 10 in any desired manner, the said dial being provided with a central opening 20 through which the forward end of bushing 14 extends. The said dial plate 19 is concentric with bushing 14 and tubular housing 15. An annular indicator ring 21 is concentrically mounted on tubular housing 15 anteriorly of said dial plate 19, so that the facing edge surfaces of the forward end of bushing 14 and ring 21 are in abutment. Ring 21 is further secured to tubular housing 15 by means of the set-screw 22. A pair of diametrically opposite indicators 23 project integrally from said ring 21.

30 As shown in Fig. 3, a supporting arm 24 is carried by the forward end of tubular housing 15, one end of said arm extending through plug 16a, and being securely retained therein by the set-screw 25. An anchoring pin P is turnably mounted on arm 24 adjacent the forward or outer end thereof. The said member P is perpendicularly disposed to said arm 24 and is composed of an upper section 26 and a lower section 27, section 26 projecting upwardly from the top planar face 50 of said arm, and section 27 depending from the

bottom planar face thereof. The ends of anchoring member P are slotted for the more secure retention of the part or half of the object or article to be mounted thereon. U represents the upper half of the body, object or article mounted on upper section 26, and L represents the lower half of the same mounted on lower section 27. It will be noted from Fig. 3 that the forward or outer end 24a of supporting arms 24, is disposed intermediate sections U and L. The invention is not to be restricted to any specific form, type or nature of the figure, body, object or article to be carried by pin section 26 and 27.

There has thus far been described the means for rotating or turning the figure or object (composed of sections U and L) about its transverse axis. When knob 16 is turned in either a clockwise or counter-clockwise direction, tubular housing 15, indicator ring 21 and its pointers 23, arm 24, and sections U and L turn in unison therewith. Ring 21 and flange 14 of bushing 13 serve to prevent any longitudinal movement of tubular housing 15 and its associated knob 16.

The small knob 28 is employed to rotate or turn the figure or object about its longitudinal axis. 29 designates a rod or shaft which is turnably mounted in tubular housing 15, the rear end of said rod extending through knob 16, and the forward end thereof extending through and beyond plug 16a and being disposed above arm 24. Small knob 28 is mounted on the rear end of said rod 29 posteriorly of said knob 16, the forward end of said rod carrying the small bevel gear 30. The said gear 30 is disposed normal to the said rod 29 and meshes with a larger bevel gear 31. The said bevel gear 31 is integral with gear 32, being spaced inwardly of the peripheral edge of said gear 32 at the top face thereof. The said gear 32 is turnably mounted on arm 24 by means of the pin 33, and meshes with the gear 34, the latter gear being integral with and carried by the upper anchoring pin section 26 adjacent the lower end thereof.

When knob 28 is turned in either a clockwise or counter-clockwise direction, rod 29 and bevel gear 30 turn in unison therewith, thereby causing gears 31, 32 and 34 to also turn therewith. Anchoring pin P is thus caused to turn, thereby rotating the figure or object about its longitudinal axis.

A small ring 35 is mounted on rod 29 the said ring being in abutment with the outer face of plug 16a. The said ring 35 and small knob 28 serve to prevent longitudinal movement of said rod 29.

If desired, the device may be provided with overhead illuminating means 36 mounted on the upper part of standard 10.

It will be observed that the means for rotating or turning the figure or object about its longitudinal axis are operatively independent from the means for turning the same about its transverse axis, although the former is carried by the latter. However, in the latter case the said indicators turn when knob 16 is turned.

As will be understood from the drawing, the figure rotation on its transverse axis is provided by the rotation of casing or housing 15, while its rotation on the longitudinal axis is provided by the rotation of rod or shaft 4, both being mounted within the support 10 with the rod carried by the casing 15. However, the position of the rod in the casing is such that each has its individual axis of rotation with such axes extending in spaced parallelism. As a result, it is evident that

during the rotation of the casing individually the rod will travel bodily with the casing, together with the gearing operated thereby, but without rotation on its own axis. Hence, the posture of the figure does not change during such movement except the change provided by the movement on the transverse axis, the travel of the rod not affecting any change in posture on the longitudinal axis, but locating the rod and its mechanism in proper position to produce the movement on the longitudinal axis at will in such changed position by the operation of knob 28. However, when rod 4 is rotated alone on its own axis of rotation, the position of the casing 15 is not affected, so that the figure change in posture is then solely on the longitudinal axis. It would require concurrent individual rotation of both knobs 16 and 28 to provide for concurrent change in posture of the figure on both the transverse and longitudinal axes, but individual rotation of the knobs will limit posture change to that of a single axis.

In other words, while rod 4 and its mechanism are movable with casing 15 when no change in posture on the longitudinal axis is desired, such movement of the rod and its mechanism is bodily and not rotative on its own axis, the advantage being that the mechanism is always in position to provide the movement of the figure on the longitudinal axis regardless of what may be the position on the transverse axis. Consequently, the figure can be moved individually on either the transverse axis or the longitudinal axis by the individual rotation of knobs 16 and 28, or can be moved concurrently on both axes by the concurrent rotation of the two knobs. The unrestricted form of either of the mechanisms is such that the figure can be rotated on either axis in a continuous path equal to a complete revolution. These results are obtainable with the simple form of mechanism disclosed through the fact that the rotation action is based upon the individual axes of rotation which extends within the support in spaced parallelism.

As evidenced by the drawings, the axis of rotation of casing 15 is aligned with the transverse axis of the figure, while shaft 4, gearing 30-34 together with knob 28 are located on one and the same side of such axis, and are symmetrically disposed relative to a radial plane extending through such axis of rotation in the direction of length of the latter. The said plane also extends through and in correspondence with the direction of length of the longitudinal axis of the figure.

As indicated in the drawings and specification, casing 15 and its knob 16 serve as a manual operator and its operating knob for rotating the figure on its transverse axis. Similarly shaft 29 and its knob 28 serve as a manual operator and its operating knob for rotating the figure on its longitudinal axis. This operator is located within the casing but is positioned therein in non-co-axial relation to the axis of the casing, the axis of the shaft is parallel to but spaced from the axis of the casing. Hence, the second operator (shaft 29) is capable of rotating as an individual to provide the figure movement about its longitudinal axis. During figure rotation on its transverse axis by casing rotation, this operator is not manually operated. However, during such casing rotation, this operator is also rotated in synchronism with the casing, due to its position within the casing, shaft 29, during the casing

rotation, advancing in a circular path as it is being carried by the casing, with the result that such advance in such path will cause the shaft periphery to shift rotatively, and thus provide the needed operator rotation without manual activity of its knob. The two operators complete a single revolution in exactly the same time and concurrently. As a result, for this movement only the knob 16 need be manually operated, knob 28 remaining untouched manually during figure rotation on the transverse axis, although the operator and its knob 28 are actually being rotated through the casing rotation.

There has been illustrated and described a preferred embodiment of the invention, but it is obvious that various changes, transpositions, and omissions may be made without departing from its spirit.

The device can be employed for art and educational observation and study; for anatomical observation and study; as an educational toy; and for any type of display. However, the invention is not to be limited to any specific use.

The invention is not to be limited to any specific size of three dimensional figure employed with the device. The figure or object may be of natural size or of any other desired size.

What is claimed is:

1. A device of the character described comprising a support, a tubular casing turnably mounted on said support, an indicator mounted on said casing and turnable in unison therewith, an arm carried by the forward end of said casing and turnable in unison therewith, an anchoring member turnably mounted on said arm, said anchoring member being perpendicularly disposed relative to said arm and casing and being composed of an upper holding section and a lower pin-holding section symmetrical about said arm, a half figure section mounted on each of said pin-holding sections, said pin-holding sections and figure sections being turnable about a trans-

verse axis of the figure through a complete revolution when said casing and arm are rotated and means carried by and movable with said casing for turning said pin-holding sections and figure halves about their longitudinal axes, said casing and said turning means each including an individual manual operator and its operating knob, the axes of said operators being non-co-axial with the operator of the turning means positioned within such operator casing, said casing and said turning means each having an individual axis of rotation within the support, said axes of rotation extending in spaced parallelism, said indicator serving to indicate positions of figure parts in different positions of adjustment on the vertical axis.

2. A device of the character described in accordance with claim 1 in which the means for turning the anchoring member and figure halves about such longitudinal axes comprises a rod having a knob at the forward end thereof and a first bevel gear at the opposite end thereof, said rod being carried by the tubular casing, the said first bevel gear meshing with a second bevel gear integral with a first gear turnably mounted on the arm, the said first gear meshing with a second gear mounted on the anchoring member intermediate the figure sections.
